ABSTRACT OF THE DISCLOSURE

A reversible scow having opposing surfaces of identical construction alternately operative as deck or bottom and provided intermediate these surfaces with a plurality of water-tight compartments, means to flood selected compartments along one side of the scow to overturn the scow and automatic self-bailing means to drain the flooded compartments in the overturned position of the scow.

This invention relates to the field of deck and dump scows and has for its objective the creation of a self-dumping and self-bailing scow of which the opposing surfaces are identical and interchangeable, and which is provided with water-tight compartments, intermediate these interchangeable surfaces, which may be selectively flooded to cause the scow to overturn completely, whereby the bottom surface becomes the deck and the deck becomes the bottom surface, thereby dumping the load carried by the scow, with means to allow the flooded compartments to empty themselves back into the sea by gravity flow. A further object is to operate the scow in this manner by remote control.

In the present state of the art, scows which are used to carry deckloads of sand, dirt, gravel or other materials are often provided with some means for dumping these loads, by devices which either incline the deck or the entire scow to a certain angle from the horizontal, thereby shifting the center of gravity of the load, whereby the load drops off the deck. After the load is removed the deck or the entire scow, as the case may be, is brought back to its original horizontal position. Because of the fact that the load is caused to drop from the deck of the scow by reason of its incline, the speed with which it is unloaded is determined by the extent of incline created, and the degree to which the scow can be inclined is limited by the danger of capsizing with too great an incline. With the present invention no such problem exists. The scow is intended to be overturned, without damage or injury, and the cargo thereby dumped with dispatch.

It is therefore the principal object of our invention to provide a self-dumping and self-bailing reversible scow which is provided with identical opposing surfaces, either of which is operative as deck or bottom, separated by water-tight intermediate compartments and provided with means to flood selected compartments to cause the scow to overturn completely, thereby dumping its load, and means to drain the flooded compartments by gravitational flow of the water therefrom.

A second important object of our invention lies in the provision of a scow, as above described, wherein the compartment flooding means and the compartment draining means function automatically, depending on the position of the scow.

A third important object of our invention lies in the provision of a scow, as above described, which can be operated by remote control.

Still another important object of our invention lies in the provision of a reversible scow which does not require drydocking for inspection, repair or maintenance.

These and other salient objects, advantages and func-

2

tional features of our invention, together with the novel features of construction, composition and arrangement of parts, will be more readily apparent from an examination of the following description, taken with the accompanying drawings, wherein:

5 FIG. 1 is a top perspective view of a preferred embodiment of our invention;

FIG. 2 is a side view of the embodiment of FIG. 1, the broken lines showing the division of the interior of the scow by bulkheads and partition into water-tight ballast tanks or compartments;

FIG. 3 is a top view of the embodiment of FIG. 1;

FIG. 4 is a diagrammatic view of the remote control valve actuator system;

10 FIGS. 5, 6, 7 and 8 are diagrammatic views showing the scow in the process of overturning and dumping its load; and

15 FIGS. 9 and 10 are diagrammatic views of modified embodiments of our invention.

20 Similar reference characters designate similar parts throughout the different views.

Illustrative of the embodiment shown by FIGS. 1-8, our reversible scow 10 comprises a pair of identical surfaces 12a and 12b, secured together by side walls 14 and 25 16, rear wall 18 and a curved front wall 20 to define a water-tight interior compartment 22. The surfaces 12a and 12b, either of which may become the deck of the scow 10, depending on the position of the scow 10 in the water as will be hereinafter explained, are parallel to one another except that they are each inclined outwardly at one end to form the banks 24a and 24b, and thereafter slope inwardly to form, with the curved wall 20, a towing header 26. Each of the surfaces or deck 12a and 12b is provided, along each side, with a pontoon-type coaming rail 28, extending respectively from the banks 24a and 24b to the rear, or stern wall 18, with each pair of rails 28 being engaged, near their rear ends, by an intermediate transverse tailgate 30, the tailgate 30 pivotally mounted to the rails 28 as shown at 32. With the tailgate 30, 35 rails 28 and respective banks 24a and 24b forming the load enclosure for the respective decks 12a and 12b. A towing bridle eye 34 is secured to each side of the front wall 20.

40 The interior compartment 22 of the scow 10 is subdivided by a central longitudinal water-tight bulkhead 36 extending from stem to stern through the compartment 22, and by a horizontal water-tight partition 38, extending from the bulkhead 36 to the side wall 14, with further bulkheads 40, 41 and 42 extending from the bulkhead 36 45 to the side wall 14, perpendicular to the partition 38, to define two upper air-tight compartments, or ballast tanks, 44 and 46, and two lower air-tight compartments, or ballast tanks, 48 and 50, the remaining area of the compartment 22 being otherwise unenclosed.

50 The side wall 14 of the scow 10 is provided with a plurality of ports 52 opening into each of the tanks 44 and 46 adjacent the partition 38, and with a plurality of ports 54 opening into each of the tanks 48 and 50 adjacent the partition 38, as shown in FIGS. 1 and 2, each of the 55 ports 52 and 54 being controlled by a flood valve 56 disposed in registry therewith. A pair of air lines 58 open into each of the tanks 44 and 46, near the partition 38, and extend through the balance of the compartment 22 and through the deck surface 12b, to define exposed exhaust tubes 60, as shown in FIGS. 5-8. Each of the lines 58 is provided with a branch line 62 which opens into and extends from an opening in the corresponding tanks 48 and 50, adjacent the deck 12b, extends therefrom in the form of an inverted V and opens into the respective air 65 line 58 intermediate its ends. Each of the air lines 58 is 70 controlled by a gravity valve 64 secured to the side wall

16 of the scow 10 and provided with a weighted arm 66 which shifts by gravitational force to open and close the valve 64, as will be hereinafter shown. A bar 68 extends from the adjacent bulkhead 40, 41 or 42 across the plane of movement of the arm 66, limiting movement of the arm to the deck 12b to close the valve 64, and to the bar 68 to open the valve 64.

Similarly, a pair of air lines 58' open into each of the tanks 48 and 50 near the partition 38, and extends through the balance of the compartment 22 and through the deck 12a to define an exposed exhaust tube 60', as shown in FIGS. 5-8. Each of the lines 58' is provided with a branch line 62' which opens into and extends from an opening in the corresponding tanks 44 and 46 adjacent the deck 12a, extends therefrom in the form of a U and opens into the respective air line 58' intermediate its ends. Each air line 58' is similarly controlled by a gravity valve 64', secured to the side wall 16 of the scow 10, provided with a weighted arm 66' whose gravitational movement to open and close the valve 64' is controlled between the deck 12a and an arresting bar 68', similarly disposed. Each exhaust tube 60 and 60' is covered by a mesh screen (not shown) to prevent foreign matter from passing through the tubes 60 and 60'.

As shown by FIG. 4, the flood valves 56 are controlled and activated selectively by means of a central remote control signal received 70 disposed within the scow 10 and connected to the respective valves 56 so that by remote control signal impulse the valves 56 located in the upper tanks 44 and 46 can be selectively opened or closed, and the valves 56 located in the lower tanks 48 and 50 can be selectively opened and closed.

In the operation of our scow 10, as shown diagrammatically by FIGS. 5-8, the empty scow 10 rides high above the water line of the body of water, ocean, lake, bay and the like, in which it is operated, with the deck 12a forming the top, or load, surface, and the deck 12b forming the bottom surface. After being loaded with load L, the scow 10 is submerged, so that its lower tanks 48 and 50 are below water level WL. One or more scows 10, similarly loaded and secured together as is well known in the art, are then towed toward their destination, by tug or other means. Upon arrival the valves 56 located in the tanks 48 and 50 are opened by remote control, the sea water flooding the tanks and the air escaping therefrom through the air lines 58' whose valves 64' have been open by reason of the gravitational position of the weighted arms 66'. As the water floods the tanks 48 and 50 the center of gravity shifts in the direction of the increased weight, and the scow 10 heels over in the direction of the arrows in FIG. 7, with the load L shifting in the same direction, until the scow 10 rolls over completely, dumping the load L into the water and exposing bottom surface 12b of the scow 10, which now becomes its deck, with tanks 48 and 50 becoming the upper tanks and tanks 44 and 46 the lower tanks. As shown in FIG. 8, due to the removal of the load L and the buoyancy created by the rails 28, the scow 10 now rides higher in the water, with the tanks 48 and 50 above water level WL. In this position and with the flood valves 56 still open, the water in these tanks begins to drain back into the sea through the respective ports 54, replaced by air coming into the tanks through the air lines 58, whose gravity valves 64 are now open. After all water has drained out of the tanks 48 and 50, the valves 56 are closed by remote control, and the scow 10 returns for another load and a repetition of the operation. This time surface 12b is the deck of the scow 10, and tanks 44 and 46 are the lower tanks to be flooded.

It is to be noted that when the scow 10 is being towed, with or without load, the tail gate 30 secured to the surface 12a or 12b, which is the bottom surface at the time, is pivotally forced into a horizontal position by the movement through the water, thereby reducing resistance to such movement.

5 Referring now to FIGS. 9 and 10, there are shown, diagrammatically, modified embodiments of our invention. In FIG. 9 the upper ballast tanks 44 and 46, and lower tanks 48 and 50, are disposed on opposite side of the scow 10', with air lines 58 and 58' suitably disposed in conformity therewith (air lines not shown). In FIG. 10, the modification is similar to the embodiment of FIGS. 5-8, except that the bulkhead 36 is off center to create larger ballast tanks 44, 46, 48 and 50 for the scow 10''. As is of course obvious, in all of these embodiments, the number, size and shape of the flooding or ballast tanks may be varied within the scope of the invention, depending on the size, shape and purpose for the scow, or similar vessel.

10 The scows 10, 10' and 10'', hereinabove described, are constructed preferably of steel, with the exception, of course, of the air lines 58 and 58', but it is to be understood that other suitable materials may be substituted, in whole or in part. Likewise, the valves 56 are preferably of the butterfly type with electric actuators, such as are well known in the art, but other types of valves or flooding means may be substituted.

15 It is also to be noted that drydocking for inspection, repair or maintenance becomes unnecessary with scows of our invention. Since the scow 10 is reversible either half may be selectively exposed for necessary attention.

20 The embodiments thus shown and described, therefore, are by way of illustration and not of limitation, and various changes may be made in the construction, composition and arrangement of parts without limitation upon or departure from the spirit and scope of the invention, or sacrificing any of the advantages thereof inherent therein.

25 Having described our invention, we claim:

1. A reversible self-dumping and self-bailing scow comprising:
30 a pair of opposing surfaces adapted alternately to become the deck and the bottom surface of the scow, each of said surfaces being curved at its front end to define a towing header and provided with coaming rails comprising water-tight pontoons along its sides and a tailgate at its rear transverse said coaming rails and pivotally mounted to the said rails, the header, rails and tailgate forming a load enclosure for the scow,
35 side and end walls securing the said surfaces in spaced relationship to one another to define an intermediate water-tight compartment therebetween, the compartment being further subdivided to define upper and lower water-tight ballast tanks, and means to flood the ballast tanks selectively to overturn the scow,
40 the said means adapted to allow gravitational drainage of the flooded ballast tanks in the overturned position of the scow.

45 2. A scow as described in claim 1, the intermediate water-tight compartment being subdivided by bulkheads and partitions to define upper and lower water-tight ballast tanks disposed along one side of the scow.

50 3. A scow as described in claim 1, the intermediate water-tight compartment being subdivided by bulkheads and partitions to define upper and lower water-tight ballast tanks along both sides of the scow.

55 4. A scow as described in claim 2, the means to flood the ballast tanks selectively comprising a plurality of ports provided in one side of the scow and opening into the said ballast tanks, a valve disposed against and in registry with each port, and air lines opening into each ballast tank and adapted to permit the flow of air out of the ballast tank during its flooding and into the tank during its drainage, the valves being selectively activated by a remote control electrical activator disposed in the scow.

60 5. A scow as described in claim 3, the means to flood the ballast tanks selectively comprising a plurality of ports provided in each side of the scow and opening into the

said ballast tanks, a valve disposed against and in registry with each port, and air lines opening into each ballast tank and adapted to permit the flow of air out of the ballast tank during its flooding and into the tank during its drainage, the valves being selectively activated by a 5 remote control electrical activator disposed in the scow.

6. A scow as described in claim 4, the opening and closing of each air line being controlled by a gravity valve.

7. A scow as described in claim 5, the opening and closing of each air line being controlled by a gravity valve. 10
